UNITED STATES PATENT OFFICE

2,667,683

SEPARATOR FOR LEASED WARP THREADS

Heinrich Meier, Uster, Switzerland, assignor to
Zellweger A. G., Apparate- und Maschinen-
fabriken Uster, Uster, Switzerland

Application March 16, 1949, Serial No. 81,671

Claims priority, application Switzerland
April 6, 1948

6 Claims. (Cl. 28—43)

1
My present invention relates to improvements in selecting and separating means for leased warp threads in warp preparation.

It is customary in the art of weaving to cross the warp by inserting two lease bands for the purpose of facilitating further warp preparation, in particular for ensuring the sequential separating of the individual threads, e. g. when knotting the warp ends. Such separation may be accomplished by hand or by means known in the art.

My present invention relates to means for separating leased warp threads through the agency of a rocking separator the axis of which is disposed parallel to the lease rods and outside the lease. Such separator comprises an element which performs, aside from the rocking movement, an axial displacing movement for the purpose of advancing the separated individual threads.

The main objects of my present invention are to afford simple means for positively separating the threads, and to simplify the operation of the separator.

Fig. 1 shows the separator in elevation, seen at right angles, and in one terminal position of its rocking movement.

Fig. 2 a top plan view thereof, including a partial axial section through a guide sleeve,

Fig. 3 the separator shortly before reaching its second terminal position,

Fig. 4 a top plan view of Fig. 3,

Fig. 5 the separator in its second terminal position, opposite hand of Fig. 1,

Fig. 6 a top plan view of Fig. 5,

Fig. 7 the separator in the same position as in Fig. 5, for illustrating a further stage of operation,

Fig. 8 a top plan view of Fig. 7,

Fig. 9 the separator after having traveled a certain distance back toward its first terminal position (Fig. 1),

Fig. 10 a top plan view of Fig. 9,

Fig. 11 the separator in its first or initial terminal position (Fig. 1),

Fig. 12 a top plan view of Fig. 11, and

Fig. 13 on a larger scale, an axial section of the separator.

In the example the separator comprises a spindle 1 (Fig. 13) which is provided with a selector wing 2 and two lateral lugs or dispatchers 3 and 4 on its end face. The spindle 1 traverses a guide sleeve 5 which is mounted rotatably on a carriage or slide (not shown). The latter is guided in known manner on rails which run transversely above the warp. The said slide

automatically follows the separation of the threads from the lease, by a feeler means of known construction, whereby the separator is always in the same position of readiness with respect to the thread to be separated at any one time. On the said slide, further, automatic control elements are mounted, which in known manner impart a rocking movement to the said guide sleeve 5 about the latter's axis. Further, actuating elements are provided on the said slide, which impart to the spindle 1 a timed reciprocating axial movement which is co-ordinated to the said rocking movement of guide sleeve 5. In this way the spindle 1 describes a helical movement. The rocking movement of the latter is transmitted onto the separator spindle 1 by means of a key 6 disposed in an internal longitudinal groove of sleeve 5. The latter, further, is provided with two lateral oppositely arranged retaining elements 7 and 8 which are formed by the straight leg of an angle piece secured to the sleeve 5, the said leg extending at right angles to the latter.

The warp is so subdivided through the two lease rods 9 and 10 into the two thread groups A and B forming the lease, that the individual threads of the said two groups alternate, which arrangement in the art of weaving is known as a 1:1 lease.

The separator at the start of the operation is moved from its initial position assumed in Fig. 1, in the direction of the arrow for the purpose of separating the frontmost thread a_1 in Fig. 2 from group A. In the position shown, the selector wing 2 exerts a certain pressure onto the threads of the groups A and B, but not onto the said frontmost thread a_1 which also is not contacted by the retaining elements 7 and 8 and which by virtue of its tension has snapped to the front of selector wing 2, thus being separated from the other threads of its row.

When the separator 5, 1 moves from the angular position of Fig. 1 to the intermediate position shown in Fig. 3, the thread a_1 is situated in front of the selector wing 2, while all the threads succeeding in the row are rearward of wing 2 and retained by the latter. Shortly before the separator 5, 1 has reached the said intermediate position, an axial movement of the spindle 1 is initiated in the direction of the arrow shown in Fig. 4, the thread a_1 passing closely by the tips of the two retaining elements 7 and 8 (Fig. 3). Upon further axial movement of spindle 1, the said thread is moved away from the non-separated threads by means of the wing 2, as shown

in Fig. 4, in which the spindle 1 has covered part of its axial travel. When, subsequently, the separator 5, 1 has arrived in its second terminal position (Fig. 5), the separated thread a_1 (Fig. 6) has been removed a considerable distance from the non-separated threads. When the separator 5, 1 rocks from the position of Fig. 3 into that of Fig. 5, the retaining element 7 has arrived in the path between the separated threads a_1 and the non-separated threads. The separator 5, 1 then first remains in its angular position shown in Fig. 5, but the spindle 1 is drawn axially into the guide sleeve 5 so as to arrive in the position shown in Fig. 8, the wing 2 releasing the thread b_1 , whereupon the wing 2 exerts a pressure onto the non-divided threads a_2, b_2, a_3 and so on. The separator 5, 1 then is rocked back into its initial position, the expelling movement of wing 2 having already been initiated in the intermediate position shown in Figs. 9 and 10, and the thread b_1 thereby having been removed from the non-separated threads. Shortly afterward the dispatching lug 4 engages the first separated thread a_1 , owing to the axial movement of spindle 1 and to the rotary movement of the latter along with the guide sleeve 5, and moves the said thread through an additional distance in the direction of separation, as may be seen in Figs. 11 and 12. In Fig. 11, the separator has returned into the initial or starting position of its rocking movement. As soon as the spindle 1 has returned from the axial position of Fig. 12 to that of Fig. 2, the separator 5, 1 has resumed its initial position as shown in Figs. 1 and 2, whereupon the cycle is repeated by separating the thread a_2 and so on.

What I claim as new and desire to secure by Letters Patent is:

1. In apparatus for separating leased warp threads of the type having two lease rods for grouping the warp thread rockably about an axis parallel to the lease rods and outside the lease, the improvement comprising the provision of a rockable shaft located outside the crossing of the threads and extending parallel to the lease rods, said rockable shaft having a first operating element and also a further operating element, said further operating element being connected with the first operating element to turn

40

50

therewith but slidably axially relative thereto, whereby combined rocking and sliding movement produces a helical movement of the further element.

5 2. In an apparatus for separating leased warp threads, the improvement set out in claim 1, in which the first separating element is a guiding sleeve for the further operating element, said further element having a spindle which passes through said sleeve axially, and means connecting said spindle with said sleeve for rotational driving, said sleeve having two retaining devices standing opposite each other for the thread group.

10 15 3. In an apparatus for separating leased warp threads, the improvement set out in claim 2, in which the two retaining devices are formed as plane surfaces.

20 4. In an apparatus for separating leased warp threads, the improvements set out in claim 3, in which the spindle has two forward lateral arms for displacing the separated warp thread.

25 5. In an apparatus for separating leased warp threads, the improvements set out in claim 1, in which the separator element is a spindle having means for separating the threads and moving the separated threads away from the warp, said spindle having two lateral lugs acting as dispatchers for the previously separated thread when displacing a freshly separated thread.

30 35 6. In an apparatus for separating leased warp threads, the improvement set out in claim 1, in which the separator element is a spindle having means for separating the threads and moving the separated threads away from the warp, a guide sleeve for transmitting rocking movement to the spindle, said spindle traversing the guide sleeve.

HEINRICH MEIER.
